(57) **CLAIM**

What is claimed is the ornamental design for a zipper pull, as
shown and described.

DESCRIPTION

FIG. 1 is an enlarged perspective view of a zipper pull, showing
the new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken lines showing a zipper slide in FIG. 1 are included
for the purpose of illustrating the invention in use, and form
no part of the claimed design.
